F. JAGER

CAR DOOR LOCKING DEVICE

Filed Dec. 31, 1919

Inventor
Frank Jager
By W. Herbert Gowles Atty.

UNITED STATES PATENT OFFICE.

FRANK JAGER, OF CHICAGO, ILLINOIS.

CAR-DOOR-LOCKING DEVICE.

Application filed December 31, 1919. Serial No. 348,695.

To all whom it may concern:

Be it known that I, FRANK JAGER, residing in Chicago, in the county of Cook and State of Illinois, have invented certain new and useful Improvements in a Car-Door-Locking Device, of which the following is a description, reference being had to the accompanying drawings, forming a part of this specification.

10 My present invention relates to improvements in door locking devices, and has reference more particularly to the provision of an improved locking and sealing device of a type designed more especially for use 15 in connection with that class of car door which is slidable longitudinally of the car door frame to close the doorway opening; one object being to improve the construction and increase the efficiency and utility 20 of devices of this type.

One of the principal objects of the invention resides in the provision of a hasp on the door post designed to co-operate with fixed and movable lock elements on the door 25 whereby to receive the seal or other ultimate securing member in such manner that the hasp is held from movement against the seal, and wherein the hasp is constructed in the form of a lever capable of manipulation 30 to materially assist in the final closing and the initial opening movements of the door.

A still further object of my invention is to produce a device of this type whose component parts are readily fabricated from 35 commercial shaped iron at a consequent reduction in initial expense and in the cost of maintenance over present devices.

These, together with such other objects 40 and advantages as may be hereinafter set forth, or are incident to my invention, I attain by means of a construction illustrated in a preferred form in the accompanying drawings, wherein:

45 Figure 1 represents a view in perspective of fragmentary portions of a door and door post to which my door operating and locking device is shown applied, the device being in locking position.

50 Figure 2 is a similar view illustrating the device in unlocked position, the door receiving its initial opening impetus by means of the hasp-lever; and,

55 Figure 3 represents a longitudinal sectional view taken through the door and post along a line immediately above the device.

In the drawings, the reference character 4 denotes the door, and 5 the door post preferably grooved to provide seats for the end member 6 of the siding at one side of the 60 projecting rib 5^a of the post 5 and for the front edge portion of the door at the other side of said rib. The outer faces of the rib and door are disposed in a common plane, 65 as will be observed.

The numeral 7 designates a combined hasp and lever which is pivoted near one end to the rib and apertured near the other end to provide an elongated slot 8. In the present instance the pivoting is accomplished by means of a headed screw bolt 9 which is partially screwed into and projects a considerable distance outwardly beyond the body of the post, through an enlarged opening in the lever which permits 75 the lever to swing outwardly from the posts as well as to pivot on said bolt.

An angle bar piece 10 having upper and lower abutments 11 and 12 is applied to the front edge of the door, by means of 80 the securing elements 13, whereby the abutments 11 and 12 extend outwardly beyond the plane of the door and at points respectively above and below the pivot bolt 9.

This arrangement of hasp-lever and the 85 abutments as thus situated with respect thereto permits of the manipulation of the former to assist in the initial opening and final closing of the door. For instance, after the slotted end of the hasp-lever has 90 been disengaged from the lock device A on the door it is moved to the left of the pivot 9 so as to engage the upper abutment 11 with its upper and short arm 7^a and with sufficient force to impart an extent of opening 95

movement to the door, in the manner indicated in Figure 2 of the drawing. Railway car doors generally are notoriously difficult to open and close, due in part to warpage and the damage resulting to moving 100 parts thereof under service conditions, but once opened to the extent suggested above such partial opening permits the exercise of leverage by the trainmen against the front edge of the door. Similarly the door is assisted in its final closing movement to closely 105 seat against the door post by manipulating the hasp-lever so as to exert a leverage against the lower abutment 12 as indicated

110 in dotted lines in Figure 1. Such a construction is particularly intended for use in connection with a car door structure such as

that described and illustrated in my co-pending application for U. S. Letters Patent, Serial Number 321,619, wherein the door is so provided with anti-frictional means permitting rapid and easy movement of the door for the major portion of its travel and a partial braking or checking of the door, to prevent slamming of the same, at its final closing and opening movements.

10 The locking device A for the hasp-lever 7 is designed, as is exactly the case with the hasp-lever and the abutment plate 10, for ready fabrication from sections of commercial shaped iron. In the present instance it 15 comprises a staple-like tongue 14 and a flange or mounting 15 for the movable locking bar 16 whose inner reduced end 17 is apertured at 17^a whereby to register with a complementary aperture 14^a formed near the 20 end of the tongue 14, so that when the hasp-lever occupies the position illustrated in full lines in Figure 1 these apertures are adapted to receive any suitable lock, such as the seal 18. This bar 16 is slotted at 19 whereby it may be manipulated by the hand-hold 25 20 in a longitudinal direction on the pin 21 which is carried by the flange 15. During this movement the bar 16 is guided and has its direction of travel maintained by its contact with the outer face of the basal flange 30 22, and in travelling in a left-hand direction, to attain the registration of the apertures 14^a and 17^a after the tongue 14 has

been passed through the hasp-lever slot 8, the reduced end portion 17^a of the bar is 35 then disposed in the path of the lever to maintain it in operative position. In this way any outward movement of the hasp-lever is taken by the end portion 17^a, and not by the seal. Upon the breaking of the 40 latter by the authorized trainman, the bar is moved to the right to release the hasp-lever which is then in readiness for use to initially actuate the door. Obviously the 45 fixed part of the locking device A comprising the elements 14, 15 and 22 may be readily made from an angle bar section, one of whose flanges may be partly cut-away at intervals to provide the elements 14 and 15. The basal flange 22 may be secured against 50 the door in line with the pivot 9 by the use of any suitable elements 23.

I claim:

The combination with a door frame, of a 55 sliding door adapted to close the opening provided by said frame, a pair of lugs fixed on said door in vertically spaced relation, and a guiding member loosely fulcrumed on said frame between said lugs in position to engage either of said lugs at will upon 60 swinging movements of the member whereby the door may be moved, said member by reason of the loose fulcrum being capable of passing either lug without engagement therewith.

FRANK JAGER.
